UNITED STATES PATENT OFFICE.

FREDERICK KLEINSMITH, OF INDIANAPOLIS, INDIANA.

SPRING-LEAF OILER.

1,351,174.

Specification of Letters Patent. Patented Aug. 31, 1920.

Application filed March 22, 1919. Serial No. 284,364.

To all whom it may concern:

Be it known that I, FREDERICK KLEINSMITH, a citizen of the United States, residing at Indianapolis, Marion county, and 5 State of Indiana, have invented and discovered certain new and useful Improvements in Spring-Leaf Oilers, of which the following is a specification.

My said invention consists in certain improvements in the details of construction and arrangement of parts of oil containers and distributors for use on leaf springs, to provide lubrication between the leaves thereof and thus avoid friction, wear and noise 10 common in the use of springs of this type which are not properly lubricated, and whereby the oil is directed into the crevices between the springs and prevented from wasting, all as will be hereinafter more fully 15 described and claimed.

Referring to the accompanying drawings which are made a part hereof, and on which similar reference characters indicate similar parts.

25 Figure 1 is a perspective view showing one end of a spring of the type referred to provided with one of my improved oiling devices.

Fig. 2, a cross section on the dotted line 30 2-2 in Fig. 1,

Fig. 3, a perspective view of the oiling device separately on a somewhat larger scale, and

Fig. 4, a detail view showing the oil hole 35 cover.

In said drawings the portions marked A represent the spring, and B the oiler.

The spring A is of any common leaf spring type.

40 The oiler B consists of a casing comprising an inner shell 10 and an outer shell 11, substantially inverted U-shape in cross section and spaced a distance apart forming a central arched bolt chamber or passageway within the inner shell and a space between the two shells, which is filled with packing to a point indicated by the dotted line 12. The bottom and ends of the chamber between the two shells are closed the end 45 closures having elongated channel bars or guides 13 extending each way therefrom with flanges 14 and 15 adapted to embrace the edge of the top leaf of the spring A. Narrow oil outlet openings 16 are formed at 50 each end of the chamber and on each side thereof. A filling opening 17 is formed in

the top of casing 11 which opening is normally closed by a plate 18 supported against the interior face of the casing on curved legs 19 and 20, as most clearly shown in 60 Fig. 4, the cover 18 being supported on a spring metal bar extending from one set of legs to the other. In filling the chamber between casings 10 and 11 the spout of the oil can is forced against the cover 18 and the 65 same depressed under the yielding of the spring bar to permit oil to flow from the oil can into said chamber onto the packing therein. As soon as the pressure of the spout of the oil can is removed the spring 70 bar returns plate 18 against the inner surface of the casing 11 and closes the oil hole against the entrance of dust and dirt.

In operation the oiler is mounted on a spring, as shown in Fig. 1, and held thereon 75 by the clip 21 and clamping bolt 22, which is a usual part of the spring structure, and being supplied with oil, as above described, said oil gradually works through the packing and discharges through the outlet passageway 16 running down into the interior of the side guide bars 13 against the lower flanges 14 thereof, said flanges 14 serving as guides to direct the oil into the recess between the top leaf of spring A and the adjacent leaf and the overflow passing down over the edge of the spring and by the movement of the spring, while the vehicle is in operation, working its way in between the other leaves of the spring, keeping them 80 lubricated for substantially their full length, as will be readily understood.

By this means the oil is given a wide distribution over the length of the spring so that it will not run down the sides of the clip 21 and waste, but will be distributed over a considerable portion of the sides of the spring and find its way between the leaves and perform the function for which it was intended. Said flanges also serve 95 the purpose of enabling the oiler to be clamped to the spring at any point along the top leaf desired, the flanges fitting over the edges of the spring the lower flange between the leaves and holding the device in 100 any position desired.

Having thus fully described my said invention, what I claim as new and desire to secure by Letters Patent, is:

1. An oiler for leaf springs comprising 110 an oil container having ends adapted to embrace the sides of the spring, said ends being

provided with bars extending each way from the oil container and formed with flanges adapted to embrace the edges of the leaf of the spring and also to serve to guide the oil lengthwise of the spring each way from the container, substantially as set forth.

2. An oiler for leaf springs comprising an oil container formed with a chamber surrounding a central passageway and having closed ends and bottom with oil outlet passages at said ends, a clamping bolt extending through said central passageway for securing said oiler in position, the ends of said chamber being provided with extension bars extending each way from said chamber and adapted to embrace the edge of the spring and serve to guide the oil lengthwise of the spring from said container, substantially as set forth.

3. An oiler for leaf springs comprising a chamber having an oil opening in its top, a cover mounted on the inside of said chamber and held over said opening by spring pressure, a packing in said chamber, closed ends with side extension arms adapted to embrace the edges of the spring, said side extension arms being formed with flanges to guide the oil each way from the oil container, substantially as set forth. 25

In witness whereof I have hereunto set 30 my hand and seal at Indianapolis, Indiana, this 18th day of February, A. D. nineteen hundred and nineteen.

FREDERICK KLEINSMITH. [L. S.]
